UNITED STATES PATENT OFFICE.

GOEFFREY DE HAVILLAND AND JOHN STANTON CHAPMAN, OF LONDON, ENGLAND,
ASSIGNEES TO THE AIRCRAFT MANUFACTURING COMPANY, LIMITED, OF WEST
MINSTER, LONDON, ENGLAND.

FUEL-SUPPLY PUMP FOR AEROPLANE ENGINES AND THE LIKE.

1,318,782.

Specification of Letters Patent.

Patented Oct. 14, 1919.

Application filed August 6, 1918. Serial No. 248,509.

To all whom it may concern:

Be it known that we, GEOFFREY DE HAVILLAND and JOHN STANTON CHAPMAN, subjects of the King of Great Britain, and residents of Edgware Road, The Hyde, Hendon, London, England, have invented a certain new and useful improvement in Fuel-Supply Pumps for Aeroplane-Engines and the like, of which the following is a specification.

This invention relates to pumps and driving mechanism therefor used for delivering fuel from the main fuel supply tank to the carburetor or to the subsidiary supply tank on an aeroplane or the like, and particularly to pumps of the gear wheel type, mounted within the main fuel supply tank and adapted to be driven through bevel gearing and a vertically-extending spindle by an aeromotor mounted on the fuel supply tank.

In a pump and driving mechanism therefor constructed in accordance with the present invention, the aeromotor is carried by a gear case of stream-line configuration enclosing the bevel gears and carried by a readily detachable cover plate serving as a closure for an opening in the tank, while the outlet of the pump is connected with an upright delivery tube which is separate from the pump-supporting tube and which passes through the cover plate and is furnished at its upper end with means for detachably coupling it to the fuel distribution pipe, the delivery tube having a relief valve and a non-return valve inserted in its length.

The invention will be described with reference to the annexed drawings, wherein Figure 1 is a side elevation, partly in section, of the main fuel tank of an aeroplane fitted with a fuel-pumping assemblage constructed in accordance with the present invention, part of the height of the tank being broken out; while Fig. 2 is an axial section of the relief valve and non-return valve, drawn to a larger scale.

3 is the main fuel-supply tank provided, for filling purposes, at its upper side with a fuel inlet closed by a detachable cap 4, and formed at its lower side with a truncated inverted cone-shaped chamber 5 having

a sheet-metal wall 6 projecting beneath the bottom of the tank 3 and secured by rivets 7 to the wall of the latter, the lower end of the chamber 5 being closed by a bottom piece 8 provided internally with an upright central socket 9 and externally with a drain-cock 10.

11 is a rotary pump of the gear-wheel type furnished with fiber rotors and bearings and inclosed in a casing provided on its under side with a central pin 12 which fits in the socket 9, whereby the pump is held in position within the chamber 5.

The pump 11 is carried by an upright metal tube 13 extending upward through the tank 3 and screwed to a boss 14 formed on the under side of a cover-plate 15 which closes the open upper end of a dome 16 mounted on the upper wall of the tank so as to surround an opening therein. The cover-plate 15 is detachably secured in position over the mouth of the dome 16 by a pair of clamping bolts 17 each of which is pivoted at its lower end to a lug 18 on the dome 16 and furnished with a butterfly nut 19 adapted to engage over a notched lug 20 on the plate 15.

The upright spindle 21 of the pump 11 is coupled at 22 to the lower end of a shaft 23 extending axially through the tube 13, the upper end of said shaft being provided with a sleeve 24 formed with a longitudinal slot 25 within which engages a cross pin 26 carried by an upright driving spindle 27. The spindle 27 is driven by means of a small aeromotor comprising a set of propeller-like vanes 28 mounted on a horizontal spindle 29 journaled in a bearing 30 in the wall of a gear case 31, which is of stream-line configuration and carried by a stool 32 integral with the cover-plate 15. The spindle 29 has fast on its inner end a bevel pinion 33 which meshes with a bevel wheel 34 fast on the upper end of the spindle 27, the latter being journaled in a bearing 35 in the gear case 31 and in a bearing 36 on the cover plate 15.

The outlet 38 of the pump 11 is connected by a screw-union 39 to an upright pipe 40 extending alongside of the tube 13, the upper end of the pipe 40 being passed through the cover-plate 15 and bent so as to

pass outward through the side wall of the stool 32, beyond which the pipe is detachably coupled by a screw-union 42 to a pipe 43 leading to the carbureter of the engine.

- 5 In the course of the upright pipe 40 are interposed a relief valve and a non-return which are shown in outside elevation in Fig. 1 and in sectional detail in Fig. 2. The relief valve comprises a downwardly-flaring 10 conoidal trumpet-mouth 44 on the lower end of a sleeve 45 which it fitted to slide over the pipe 40, the lower margin of the trumpet-mouth 44 constituting the valve-face which normally closes against a fixed seating 46 15 provided upon a flange 47 which projects radially around a section of the pipe 40 supported in a pair of upper and lower brackets 48, 49 fixed to the pump-carrying tube 13, while immediately above the flange 47 a 20 series of apertures 50 in the wall of the pipe 40 open from the interior of the latter into the space 51 inclosed between the pipe and the trumpet-mouth. The sleeve 45 and trumpet-mouth 44 are pressed downward, so 25 as normally to hold the relief valve closed, by a spring 52 coiled in compression about the sleeve 45 and pipe 40 between the outer surface of the trumpet-mouth 44 and the upper bracket 48, so that, on the pressure 30 within the pipe 40 and space 51 exceeding the resistance due to the spring 52, the valve will be forced upward and allow the escape of the liquid fuel from the pipe.

Above the bracket 48, the upright pipe 35 40 is provided with a local enlargement 53 constituting a chamber for the accommodation of the non-return valve, which comprises a ball 54 normally resting by gravity upon a seat 55 surrounding the mouth of the 40 pipe 40 within the chamber 53, the two pins or wires represented by the small circles 56, extending transversely of the chamber 53, some distance above the normal position of the ball 54, forming a stop to limit the upward movement of the ball.

It will be seen that the above described construction permits ready removal from the tank 3 of the pump 11, pump-carrying tube 12, aeromotor 28, and gear case 31, with 50 their immediate adjuncts, all as a self-contained unit, when the pipe 40 has been uncoupled from the pipe 43 at the union 42 and the clamping-bolts 17 have been unfastened.

55 We claim:

1. In an aeroplane or the like, provided with a main fuel supply tank and a carbureter or subsidiary tank, said main tank having a flanged opening, means for transferring fuel from the main tank to the carbureter or subsidiary tank, comprising a pump, adapted for drawing fuel from the bottom of said main tank, a discharge pipe leading from the pump to said subsidiary 60 tank and an aeromotor or the like power 65

element for continuously operating said pump while the aeroplane is flying, said pump, the discharge pipe, and said aeromotor being mounted upon and supported by a cover plate adapted to fit said flanged opening, thereby adapting them to be removed as a unit, and means for securing the cover plate to the flanged opening, substantially as described. 70

2. In an aeroplane or the like, provided with a main fuel supply tank and a carbureter or subsidiary tank, means for transferring fuel from the main tank to the carbureter or subsidiary tank, comprising a pump supported in the main tank by a tube 75 adapted to inclose the driving shaft of the pump, a well in the main tank in which said pump is located, said main tank being provided with an opening opposite said well, a cover plate for said opening with which said pump supporting tube is connected, an aeromotor mounted upon said cover plate and geared to said shaft for operating said pump and a discharge pipe leading from the pump through said cover plate and adapted to be 80 connected with said carbureter or subsidiary tank, substantially as described. 85

3. In an aeroplane or the like, provided with a main fuel supply tank and a carbureter or subsidiary tank, said main tank 95 having a flanged opening, means for transferring fuel from the main tank to the carbureter or subsidiary tank, comprising a pump suspended within the main tank through said opening therein, a cover plate supporting said pump and adapted for closing said cover plate, an aeromotor connected by gearing with said shaft and a gear-case of stream-line configuration mounted upon said cover plate and inclosing said gearing substantially as described. 100

4. In an aeroplane or the like, provided with a main fuel supply tank and a carbureter or subsidiary tank, said main tank having an opening therein and a tank-well 110 below and opposite said opening, a cover plate for said opening, a pump located in said tank-well and suspended from said cover plate, pin and socket engaging means between the pump and said tank-well and a 115 motor supported on said cover plate for driving said pump, substantially as described.

5. In an aeroplane or the like, provided with a main fuel supply tank and a carbureter or subsidiary tank, means for transferring fuel from the main tank to the carbureter or subsidiary tank, comprising a pump supported in the main tank by a tube adapted to inclose the driving shaft of the pump, a well in the main tank in which said pump is located, said main tank being provided with an opening opposite said well, a cover plate for said opening with which said pump supporting tube is connected, an aeromotor 125 130

mounted upon said cover plate and geared to said shaft for operating said pump, a discharge pipe leading from the pump through said cover plate and adapted to be connected with said carbureter or subsidiary tank, and a spring actuated relief valve in said discharge pipe, substantially as described.

6. In an aeroplane or the like, provided with a main fuel supply tank and a carbureter or subsidiary tank, means for transferring fuel from the main tank to the carbureter or subsidiary tank, comprising a pump supported in the main tank by a tube adapted to inclose the driving shaft of the pump,

10 15 a well in the main tank in which said pump is located, said main tank being provided with an opening opposite said well, a cover plate for said opening with which said pump supporting tube is connected, an aeromotor mounted upon said cover plate and geared to said shaft for operating said pump, a discharge pipe leading from the pump through said cover plate and adapted to be connected with said carbureter or subsidiary tank, and a non-return valve inter-

posed in said discharge pipe, substantially as described.

7. In an aeroplane or the like, provided with a main fuel supply tank and a carbureter or subsidiary tank, means for transferring fuel from the main tank to the carbureter or subsidiary tank, comprising a pump supported in the main tank by a tube adapted to inclose the driving shaft of the pump, a well in the main tank in which said pump is located, said main tank being provided with an opening opposite said well, a cover plate for said opening with which said pump supporting tube is connected, an aeromotor mounted upon said cover plate and geared to said shaft for operating said pump, a discharge pipe leading from the pump through said cover plate and adapted to be connected with said carbureter or subsidiary tank, a spring actuated relief valve and a non-return valve suitably interposed in said discharge pipe, substantially as described.

GEOFFREY DE HAVILLAND.
JOHN STANTON CHAPMAN.
